UNITED STATES PATENT OFFICE.

ALBERT BOWN, OF STREATOR, ILLINOIS, ASSIGNOR OF ONE-HALF TO
FAWCETT PLUMB, OF SAME PLACE.

ENGINE.

SPECIFICATION forming part of Letters Patent No. 339,136, dated April 6, 1886.

Application filed November 17, 1885. Serial No. 183,128. (No model.)

To all whom it may concern:

Be it known that I, ALBERT BOWN, of Streator, in the county of La Salle and State of Illinois, have invented certain new and useful 5 Improvements in Engines; and I do hereby declare the following to be a full, clear, and exact description of the invention, such as will enable others skilled in the art to which it appertains to make and use the same.

10 My invention relates to an improvement in engines.

The object is to provide a multiple-cylinder engine in which a single steam-chest shall answer for all the cylinders and be capable of 15 accommodating slide-valves and valve-operating gear of improved construction.

With these ends in view my invention consists in certain features of construction and 20 combinations of parts, as will be hereinafter described, and pointed out in the claims.

In the accompanying drawings, Figure 1 is a view of the engine in vertical longitudinal section. Fig. 2 is a transverse section through the steam-chest and one of the cylinders; and 25 Fig. 3 is a view of the steam-chest in elevation, the cover being removed to show the valve-gear in position.

A A', &c., represent two or more cylinders (in the present instance three) supported upon 30 a hollow base, B, containing oil and water. The engine-shaft C extends through the base B, and has suitable bearings in each end. The shaft C is cranked at points in a line with the axes of the cylinders. The three cranks c c' c' 35 diverge from the axis of the shaft in radial planes, forming equal angles with each other, and their wrist-pins are connected with the pistons P by the piston-rods p.

D represents a valve-chamber, which extends 40 across the several cylinders, serving as a common valve-chamber and steam-chest for all the cylinders. Steam-ports S extend from the cylinders above the pistons to the valve-chambers, and exhaust-ports E lead from the valve-chamber to the exhaust-pipes e, located at 45 either one or both ends of the engine.

V represents slide-valves of ordinary construction, one of which is adapted to open and close the ports of each of the cylinders. They 50 are adjustably connected to yokes Y, which latter engage wrist-pins x on the cranked por-

tions of the valve-operating shaft X. The shaft X extends through the valve-chamber, and is journaled in its ends, and its cranked portions are constructed to slide the valves V 55 successively over the ports in the several cylinders, as eccentrics on the engine-shaft would do in the ordinary construction. The cranked portions of the shaft X radiate from the axis of the shaft in planes which make equal angles 60 with each other, and thus some one of the pistons is constantly in a position to do its most effective work. The valve-shaft X is conveniently driven by means of gear G G' G², the gears G and G² having the same number of 65 teeth. Other means, however, might be employed to transmit the motion of the shaft C to the valve-shaft X.

The bearings within the valve-chamber are kept lubricated by admitting oil with the 70 steam, and the pistons may either be lubricated through the medium of the live steam or from the oil and water in the hollow base.

It is evident that eccentrics might be employed on the valve-shaft within the steam-chest in the place of cranks, and that other slight changes might be resorted to in the form and arrangement of theseveral parts described without departing from the spirit and scope of 75 my invention; hence I do not wish to limit 80 myself strictly to the construction herein set forth.

I am aware that a multiple-cylinder engine having a valve-chamber common to all of said cylinders and a single slide or rotary valve operated by a shaft having eccentrics thereon is 85 not new; hence I make no claim to such a construction.

Having fully described my invention, what I claim as new, and desire to secure by Letters 90 Patent, is—

1. The combination, with a series of cylinders located side by side, a valve-chamber common to said series of cylinders, a single port connecting each cylinder with the valve-chamber, and an exhaust-port for each cylinder opening into the valve-chamber, of a slide-valve for each cylinder, and a single shaft located within the valve-chamber, and having a series of cranks adapted to operate the valves, 95 substantially as set forth.

2. The combination, with two or more cylin-

ders, pistons working in the cylinders and adapted to receive steam on one side only, and a cranked engine-shaft driven by the pistons, of a valve-operating shaft having a series of 5 cranks or eccentrics thereon and located within the valve-chamber, a series of sliding valves operated by said valve-operating shaft, and gearing connecting the engine-shaft and valve-operating shaft, substantially as set forth.

10 3. The combination, with sliding valves located in a valve-chamber common to two or more cylinders, of yokes to which the valves

are adjustably secured, and a rotary shaft passing longitudinally through the valve-chamber, and provided with eccentric or cranked portions adapted to engage the yokes and operate the valves, substantially as set forth. 15

In testimony whereof I have signed this specification in the presence of two subscribing witnesses.

ALBERT BOWN.
